(57) **CLAIM**

The ornamental design for an automotive cleaning brush, as shown and described.

DESCRIPTION

FIG. 1 is a perspective view of a new and ornamental design for an automotive cleaning brush;

FIG. 2 is a front elevation view thereof;

FIG. 3 is an enlarged, fragmentary perspective view thereof;

FIG. 4 is a first side elevation view thereof;

FIG. 5 is a first side elevation view thereof;

FIG. 6 is a top plan view thereof;

FIG. 7 is a bottom plan view thereof; and,

FIG. 8 is an enlarged perspective view of the upper portion of the brush which is fragmentarily shown for clarity and ease of illustration.

The dash-dot broken line represents the bounds of the claim and forms no part thereof and the dashed broken lines showing the bristles and the top and interior surfaces of the coupling feature illustrate portions of the brush that form no part of the claimed design.
